UNITED STATES PATENT OFFICE.

JAMES WHITCOMB, OF SAN JOSÉ, CALIFORNIA.

WHIFFLETREE.

SPECIFICATION forming part of Letters Patent No. 297,734, dated April 29, 1884.

Application filed January 8, 1884. (No model.)

To all whom it may concern:

Be it known that I, JAMES WHITCOMB, of San José, in the county of Santa Clara and State of California, have invented a new and useful Whiffletree, of which the following is a specification.

The objects of my invention are to provide a whiffletree attachment whereby the resistance at the initial or starting point is greatly relieved, and at the same time the whiffletree largely strengthened, as well as ready means for connecting the tug loops or irons. I accomplish these objects by the means illustrated in the accompanying drawings, in which—

15 Figure 1 is a plan of my improved whiffletree. Fig. 2 is a cross-section taken on the line XX. Fig. 3 is a cross-section taken on the line Y Y of Fig. 1; Fig. 4, a vertical section of the clip and set-screw for increasing the 20 tension of the spring. Fig. 5 is a detail view of one end of the whiffletree.

Similar letters refer to similar parts throughout the several views.

A represents the wooden portion of my whiffletree, which is beveled or inclined along the 25 rear edge from the center or greatest thickness to the ends thereof, as shown in Fig. 1. Along this beveled edge is placed a flat piece of steel, B, of sufficient thickness to provide 30 a spring of the required tension, the ends of which are rounded, so as to pass through holes C, made in the ends of the whiffletree, and bent inwardly to form hooks D for the tug irons or loops. Upon the wooden portion of the whiffletree are placed open-ended clips or angle- 35

irons E, which are held by bolts F, and midway between these angle-irons or in the center of the whiffletree is placed a fixed band, G, secured by the bolt G'. In the outer end of the band is a set-screw, H, the end of which 40 acts against the spring-bar and causes it to become more or less rigid as the screw is tightened up or loosened, and also serves to hold the bent ends of the hooks more firmly against the face of the wooden bar and impart a greater 45 resilience to the spring, the open-ended angle-irons acting as fulcrums against which the spring-bar acts.

Having thus described my invention, what I claim, and desire to secure by Letters Patent, 50 is—

1. In a whiffletree having a continuous spring-bar, the fixed band G, provided with a set-screw, H, which, by tightening or loosening causes the spring-bar to act with a greater 55 or less resilience, substantially in the manner as herein set forth and specified.

2. The combination and arrangement of the beveled wooden bar, continuous spring-bar, angle-irons or fulcrum, and the fixed band provided with the adjusting set-screw, constructed and operating substantially in the manner as herein set forth and specified. 60

In testimony that I claim the foregoing I have hereunto set my hand and seal.

JAMES WHITCOMB. [L. S.]
